UNITED STATES PATENT OFFICE.

JOSEPH A. MISLAND, OF NEW YORK, N. Y.

COMMUTATOR BRUSH AND HOLDER FOR DYNAMOS AND THE LIKE.

No. 840,506.

Specification of Letters Patent.

Patented Jan. 8, 1907.

Application filed December 7, 1905. Serial No. 290,738.

To all whom it may concern:

Be it known that I, JOSEPH A. MISLAND, a citizen of the United States, residing in the borough of Brooklyn, in the county of Kings, in the city and State of New York, have invented certain new and useful Improvements in Commutator Brushes and Holders for Dynamos and the Like, of which the following is a specification.

- 10 This invention relates to the contact-brushes used on the commutators of dynamos and electric motors, and to the holders for such brushes; and the object is to provide for the proper contact of the brushes at all times, especially when the motor or dynamo is reversed, so that full contact may be had at all times and under all conditions and sparking or the formation of corroding arcs at the commutator is avoided.
- 20 It is a known fact that in the use of solid brushes bearing radially on a cylindrical commutator which is liable to be rotated in either direction the frictional peripheral contact of the periphery of the commutator running in one direction tends to and does deflect or swing the brush so as to wear the contact end of the brush off most at the back or rear corner and that when the commutator is reversed the brush is swung the other way and 30 a bad contact is the result. The worst effect of this is the formation of arcs, which eat or burn away both the commutator and brush, and thus increase the difficulty. This is due to the fact that the brush must be fed up to the commutator radially to the latter as the brush wears away, and the necessity for this freedom of movement in feeding involves always some lateral play of the brush whereby in the constructions now in use in the reversal of the direction of rotation the drag of the commutator on the brush shifts the latter out of its proper radial position first in one direction and then in the other.
- 40 The present invention provides a means for holding the brush up to the periphery of the commutator squarely and radially at all times and for feeding it forward as it wears away.

50 In the accompanying drawings, which illustrate an embodiment of the invention, Figure 1 is a side elevation of the brush and its holder. Fig. 2 is a rear elevation as seen from the right in Fig. 1. Fig. 3 is a transverse section at line x^3 in Fig. 2. Fig. 4 is a vertical section at line x^4 in Fig. 2. Fig. 5 is

a detached view of the socket-plate of the brush detached.

In the views, C designates a part of any cylindrical commutator of a dynamo or electric motor, and B is a part of the bracket on the frame to which the brush-holder is secured. These features are well known in the art and will need neither illustration nor elaborate description.

The holder 1 may be cast metal adapted to receive one or more brushes 2 of the usual material and of oblong block-like shape. The brush has fixed to it and recessed in its face a metal socket-piece 3. (Seen detached in Fig. 5.)

70 Mounted in the frame are rollers 4, against which the upright brush is pressed by a spring-plunger 5. This plunger has a rounded end 6, which engages the socket in the socket-piece 3, and it has near its outer end a loose bearing at 7 in a frame 8 on and forming substantially an integral part of the holder 1. The plunger 5 is disposed obliquely to the face of the brush, and the plunger-spring 9 is embraced between a shoulder 10 on the plunger in the frame 8, as clearly shown in Fig. 4. On the outer end of the plunger is a nut 11 and limiting-washer or stop 12.

75 It will be noted that the brush is always radial to the commutator, as indicated by the dotted line z in Fig. 1, and that as it wears away the pressure of the plunger obliquely on it keeps it pressed up closely to the periphery of the commutator. At the same time the spring-plunger prevents the brush from swinging or being dragged out of its radial position when acted upon by the frictional contact of its end with the periphery of the rotating commutator, no matter in which direction the latter may be rotating. The bearing 7 is of such a form that it permits the plunger to adapt itself to the slight change in obliquity it must assume as the brush gradually wears away. Preferably there will be two or more brushes in the frame rather than one wide brush, and the brush will be embraced at its edges by flanges on the holder to prevent edgewise movement.

105 The rollers 4, disposed back of the brush, so as to take the pressure from the spring-plunger, is very important, as the bearing of the brush on a flat stationary surface, as in the ordinary construction, would produce so

much friction as to render the feeding of the brush irregular and uncertain. The rollers should be so placed that the bearing-point of the plunger 5 on the brush will be at a point between the outer and inner rollers, as clearly shown in Fig. 4. This distributes the pressure between the rollers and prevents chattering.

The socket-piece 3 may be considered in a structural sense a part of the brush. As the brush is usually made from some relatively weak and soft non-metallic material and it is necessary for the oblique plunger to find a bearing thereon, the socket-piece shown is provided. This device may be considered as a bearing-piece or piece to take the wear and provide a suitable step to receive the end of the plunger. It is in this sense that the word "socket" is used herein.

Having thus described my invention, I claim—

1. A commutator-brush provided with a socket 3, set into the brush and provided with a concave recess, in combination with a holder for the brush provided with roller-bearings for the latter, and with a spring-plunger having a convex end engaging the socket on the brush, said plunger being disposed obliquely to the face of the brush and

having a loose bearing at 7, to enable it to vary its obliquity.

2. A commutator-brush provided with a socket set into the brush and provided with a concave recess, in combination with a holder for the brush provided with a spring-plunger having a convex end engaging said socket in the brush, said plunger being disposed obliquely to the face of the brush and having a loose bearing to enable it to vary its obliquity.

3. The combination, with a commutator-brush, provided with a socket-piece 3, set in its face, of a holder 1, having in it a guideway for the brush, rollers on which the back of the brush bears, a frame 8, and a spring-plunger mounted loosely at 7, in said frame with its rounded end engaging the socket on the brush, said plunger having its axis oblique to the axis and the direction of movement of the brush.

In witness whereof I have hereunto signed my name, this 5th day of December, 1905, in the presence of two subscribing witnesses.

JOSEPH A. MISLAND.
